UNITED STATES PATENT OFFICE.

JAMES B. McCUTCHEN, OF BAKERSFIELD, CALIFORNIA.

AUTOMATIC DOOR CLOSING AND LOCKING MEANS.

Application filed September 3, 1924. Serial No. 735,558.

This invention relates to safety alarm devices.

The general object of the invention is to provide an improved burglar alarm and 5 trapping device.

One of the specific objects of the invention is to provide a robber trapping device which may be applied to the usual type of door in use in banks, counting houses, and other 10 buildings.

Another object of the invention is to provide means operable at will to lock a door already closed and simultaneously sound an alarm.

15 Another object of the invention is to provide means for automatically closing an open door, locking it, and simultaneously sounding an alarm.

20 A further object of the invention is to provide a novel mechanism or device which will lock a door already closed or if a door is open will cause the door first to close and then to be locked, both locking operations being accompanied by the sounding of an 25 alarm.

Other objects of the invention will be apparent from the following description taken in connection with the following drawings wherein Fig. 1 is an elevation showing one 30 embodiment of my invention; Fig. 2 is a cross section showing the details of the operating mechanism of my invention; Fig. 3 is a view similar to Fig. 2 showing a modified form of the invention; Fig. 4 is a section on line 4—4, Fig. 2; Fig. 5 is an enlarged section on line 5—5, Fig. 2; and Fig. 35 6 is a wiring diagram.

Referring to the drawings by reference characters, I have shown doors at 10. These 40 doors are indicated as arranged in a pair although it will be understood that my invention is clearly applicable to single doors. Each door 10 is illustrated as provided with a door closing device 11 which may be of the 45 character in common use for closing doors.

Arranged above the doors 10 I show a casing 12 which may have an ornamental front portion 14 thereon. This front portion 14 is provided with hinges 14' and with a lock 50 14'', as shown in Fig. 4. This casing is indicated as provided with a spring pressed locking member 15. This locking member comprises two bolts 16 having a common shank 17 which is normally urged downward 55 by means of a spring 18. Each door 10 is provided with a keeper 20 for the bolts 16.

The lower end of the bolts 16 each have a bevel 21 so that when the doors 10 are moved to closing position, the beveled portion will ride over the top of the door 10 compressing 60 the spring. When the door is fully closed the bolts will be moved to operative position by means of the spring 18.

A collar 25 is indicated as mounted upon the shank 17. This collar is shown as engaged by a trigger 26 which is normally urged to operative position by means of a spring 27. The trigger 26 may be mounted for movement between ball races 28.

The trigger 26 is shown as connected by 70 means of a cord or cable 30 with an operating lever 31 mounted in a receptacle 32. The cable 30 is preferably arranged within an ornamental moulding 33 as shown in Fig. 1. The operating lever 31 is mounted on a pivot 75 34 and is adapted to be rocked by means of a lever 35 pivoted as at 36 and having its end 37 pivotally mounted upon the armature core 38 of an electro-magnet or solenoid 39. The electro-magnet is of the type where the 80 core or armature extends entirely therethrough.

The lower end of the solenoid 39 is pivotally connected as at 40 with a lever 41 which in turn is pivoted at 42 within the casing. 85 The lever 41 is provided with a flange 45 at its outer end with an inclined portion 46 adjacent the flange. The lever 41 with its flange 45 is so mounted that this flange will engage the face of the door and thus normally hold the door open. The tendency of the door closing device 11 is constantly to 90 close the door. The engagement of the shoulder 45 prevents this action.

Referring to Fig. 6 I show means for operating the lever 41 comprising a battery 50 having a lead 51 extending to a switch 52 whence the lead 53 extends to the solenoid 39 and through the lead 54 to the battery.

Operation of the solenoid will move the 100 core upwardly thus lifting the lever 41 and releasing the door. At the same time the door is released the lever 31 will be rocked thus pulling the cable 30 and moving the trigger 26 from engagement with the collar 105 25. This enables the bolts 16 to be pushed down by means of a spring 18. When the door has advanced far enough the edge of the door will engage the bolt 16 and push it upwardly until the door has closed after 110 which the bolt will move to operative locking position.

In order to simultaneously sound an alarm at the same time the door is closed, I show the collar 25 as provided with an insulated circuit closer 60. This circuit closer is 5 adapted to bridge the spaced terminals 61 which are insulated from the casing 14. One of the terminals 61 is connected by means of a lead 62 with the battery 50 while the other terminal is connected by a lead 63 with a bell 10 64 whence a lead 65 extends to the battery 50. It will thus be apparent that when the bolts 16 move to operative position the electric bell 64 will be operated.

My device is also adapted for use with 15 safety devices which includes panels 70 as shown in Fig. 6. The panel contains a plurality of wires 71 and 72 which are part of a closed circuit to the battery 50. This closed circuit includes a solenoid 73. So 20 long as current flows through the solenoid it will be maintained in the position shown in Fig. 6. When, however, through surreptitious or other operation the circuit through the leads 71-72 is broken the pulling 25 effect of the solenoid 73 will cease and the circuit closer 74 will be released so that it can move and thus bridge the terminals 75 shown in Fig. 6. One of the terminals 75 is connected by a lead 76 with the lead 53 while 30 the other terminal 75 is connected by a lead 77 with the lead 51. It will thus be apparent that when the circuit 71-72 is broken, as by a robber entering the building, the door latching mechanism will operate and the 35 alarm 64 will sound.

In operating my device, the person who has observed the robber will close the switch 52 thus operating the solenoid 39. If the door is open the door will be released and 40 will close gradually. At the same time the trigger will release the bolts so that when the door is completely shut it will be engaged and held by the bolts. If, however, the door is already closed the lever 41 will merely be 45 raised up idly and the trigger 26 will be operated to lock the door. The bell will ring as the door is being locked and will continue to ring.

In order that my device may be manually 50 operated I show a construction in Fig. 3 including a casing 100 which is preferably similar in all respects to the casing 14 previously described. In order to operate the trigger mechanism 101 I show a cable 102 connected to a bell crank 103 which is adapted to be rocked by pulling a cable 104 provided with a hand gripping portion 105' and a foot pedal 106'.

The bell crank 103 is secured to a pivotally 60 mounted lever 104 having a flange 105 for holding a door closed. A switch 106 which may be similar in all respects to the switch 60-61 previously described, may serve to close the circuit to a bell 107 which may be 65 operated by a dry battery.

From the description of the modification it will be apparent that when the banker or his employees desire to close the door or to lock it they may grasp the handle 105' or they may step on the pedal 106' to thus release the door if it is open and to lock it. If the door is closed it will be locked. After the device has been released, to reset it, the lock 14" will be released and the front portion 14 will be swung on the hinges 14' so 75 that the locking member 15 and the associated parts will be exposed. The locking member 15 will then be moved to set position after which the trigger 26 will move to the position shown in Fig. 2.

From the foregoing description it will be apparent that my device will lock a closed door and if the door is open will cause the door to be closed and then to be locked.

Having thus described my invention, I 85 claim:

1. In a device of the class described, a door pivoted to swing about a vertical axis, means to hold said door open, means to close said door when open, means to release said holding means, a latch independent of said door holding means for holding said door closed, the operation of said releasing means serving to move said latch to operative position.

2. In a device of the class described, a door pivoted to swing about a vertical axis, latch means to hold said door against opening, said latch means being operable at will, means to close said door when open, means independent of said latch means to hold said door open, and electrically operated means for releasing said holding means and for operating said latch means regardless of whether the door is open or closed.

3. In a device of the class described, a hinged door, means to lock said door in closed position, said means including a slideable bolt, means for urging said bolt to operative position, a trigger for holding said bolt inoperative, a door holding member said member being independent of said bolt and a single means for causing actuation of said door holding member and said trigger.

4. In a device of the class described, a casing having a door hinged thereto, means to lock said door in closed position, said means including a plunger, releasable means for holding said plunger inoperative, an operating cable for actuating said releasable means, a lever on which said operating cable is secured, means to move said cable, a door holding member movable independently of said plunger, and means whereby said door holding member may be operated by said last mentioned means.

5. In a device of the class described, a casing having a pair of doors hinged thereto, means to lock said doors in closed position, said means including a plunger having a

- pair of spaced bolts thereon each of which is adapted to engage one of said doors, a spring for pressing said plunger to operative position, a trigger engaging said plunger for holding said plunger inoperative, means to normally hold said trigger in engagement with the plunger, an operating cable for said trigger, a lever on which said operating cable is secured, means to rock said lever to operate said cable, a door holding member and means whereby said door holding member may be operated by said first mentioned means to release the door.
6. In a device of the class described, a casing having a door hinged thereto, means to lock said door in closed position, said means including a plunger having a bolt thereon which is adapted to engage said door, a spring for pressing said plunger to operative position, a trigger for holding said plunger inoperative, a spring normally urging said trigger against said plunger, an operating cable for said trigger, a lever on which said operating cable is secured, means
- 5 to rock said lever, said means comprising a solenoid, a door holding member and additional means whereby said door holding member may be operated by said solenoid to release the door.
7. In a door actuating device, a casing, 30 said casing having a pair of doors hinged thereto, means to lock said doors in closed position, said means including a plunger having a pair of spaced bolts thereon each of which is adapted to engage one of said doors, a spring for pressing said plunger to operative position, a trigger for holding said plunger inoperative, means to normally hold said trigger operative, an operating cable for said trigger, a lever on which said operating 40 cable is secured, means to rock said lever, said means comprising a solenoid, a door holding member and means whereby said door holding member may be operated by said solenoid to release the door.
- 45 In testimony whereof, I hereunto affix my signature.

JAMES B. McCUTCHEON.
